ATTORNEYS:

UNITED STATES PATENT OFFICE.

PHILIPPE BOUCHER, OF WOONSOCKET, RHODE ISLAND.

DESIGN FOR A BADGE.

SPECIFICATION forming part of Design No. 35,088, dated September 17, 1901.

Application filed August 8, 1901. Serial No. 71,414. Term of patent 7 years.

To all whom it may concern:

Be it known that I, PHILIPPE BOUCHER, a citizen of the United States, residing at Woonsocket, in the county of Providence and State of Rhode Island, have invented and produced a new and original Design for a Badge, of which the following is a specification, reference being had to the accompanying drawings, forming part thereof.

Figure 1 is a front view of the badge, showing my new design. Fig. 2 is a sectional view of the badge.

As shown in the drawings, the leading or material feature of my design consists of the conventional representation of a cross resting on a support surrounded by a triangle studded with stars. Two flagstaffs extend

from the center of the cross in oppositely-inclined directions and support two flags draped on opposite sides behind the lateral arms of the cross to correspond with the circular central panel surrounded by an annular ring.

Having thus described my invention, what I claim as new, and desire to secure by Letters Patent, is—

The design for a badge, as herein shown and described.

In testimony whereof I have signed my name to this specification in the presence of two subscribing witnesses.

PHILIPPE BOUCHER.

Witnesses:

ADA E. HAGERTY,
JOSEPH A. MILLER.
